TUBE BENDER

Charles B. Small and Anton J. Janik, Elyria, Ohio,
assignors to The Ridge Tool Company, Elyria,
Ohio, a corporation of Ohio

Filed Mar. 21, 1962, Ser. No. 181,327

4 Claims. (Cl. 72—35)

This invention relates to tubing or rod benders and more particularly to a tubing or rod bender of the hand-held type which may be used to bend tubing or rods to provide predetermined angles of bend as well as to enable tubing or rods to be bent wherein the laterally or angularly extending portions are of predetermined length and the length of the connecting portions therebetween may be predetermined.

Tubing benders of the class described usually comprise a grooved mandrel, about which and in the groove of which a tube may be bent. A handle is conveniently attached to the mandrel and a bending shoe or roller having an operating handle is either connected by a link or directly to the axis of the mandrel. A tube is placed alongside the handle, with the place to be bent disposed in the mandrel groove and then the shoe, by means of the handle on the shoe, is brought into contact with the side of the tube which projects outwardly from the sides of the mandrel and rotated around the mandrel to effect the bending. The foregoing is all old in the art as exemplified by Patent No. 1,824,026, of September 22, 1931.

One of the problems of the prior art has been to hold the tube so that it does not slip around the mandrel as it is being bent. Although this, in many instances, is not too serious a defect, when it is desired to make exact bends in exact places such slipping cannot be tolerated. Heretofore it was common practice to provide a hook or latch, as shown in the aforesaid patent, which was pivotally mounted on the handle adjacent the base of the mandrel and which could be swung over and engage with the tube, which extended parallel to the handle. Although the hook served to prevent the base leg of the tube from swinging out during the bending operation, it did not always prevent the tube from the aforesaid sliding during the bending operation, particularly when the tubing was of the harder drawn type.

In addition to the foregoing, the main handle was usually disposed away from the tube in spaced parallel relation and in some instances was provided with an offset to assure that it was in such spaced relation in order that the operator could grasp the handle without interference from the tube. The result was, that frequently the operator grasped both the tube and the handle at the same time causing the tube to be bent at a place where it was not intended to be bent or upsetting the number of degrees of bend at the place where it was supposed to be bent. Sometimes the operator's hand pushed the tube in the other direction away from the handle, making an undesired reverse bend.

By the present invention we have provided a bending tool where the tube, which extends tangent to the bottom of the groove in the mandrel at the bend starting point, is also seated in a longitudinally extending seat co-extensive with the handle and the bottom of which extends in alignment with the bottom of the groove in the mandrel and on a line tangent to the mandrel at the starting point.

The above feature provides several advantages. Since the tube is seated in the handle groove, both the tube and the handle are grasped at the same time, such gripping causes the tube to be firmly seated in the handle and the friction of the tube with the bottom and sides of the groove resists the tendency for the tube to shift longitudinally during the bending operation.

In addition to the above, the hook or latch for holding

2

the tube provides an additional function to that of merely holding the base leg from outward swinging in that it also presses the tube into the groove, and, with the improved design of hook, which has a cam surface for engaging the tube, causes the tube to be held against slippage even where the portion which is disposed in the groove is so short as to not be conveniently engaged by the fingers of the operator.

The seating of the tube in the handle provides an additional advantage in that the handle, with the tube in position, may be placed in a vise so that on one side one of the jaws engages the handle and the other jaw engages with the tube and presses it into the seat. The depth of the groove is sufficient that the tube is not unduly squashed out since the sides of the groove prevent this result, providing, of course, that normal clamping pressure is used.

Still another advantage resides in the fact that measuring means may be incorporated with the handle with the markings extending up to the edge of the groove and thus markings on the tube may be made at exact dimensional places or previous markings on the tube may be aligned with the marking on the handle to provide more exactitudes of placement of the bends or determining the length of unbent portions beyond the bends. Another feature is that when the tube is in the groove the edge of the groove may be used as a straight edge to enable marking of the tube longitudinally, which marking may be subsequently used to make sure that the bend is in the desired plane.

Another feature of the invention resides in the fact that, with the handle and its groove as stated, the handle and mandrel may be made as one integral element, thus lessening the assembly operations and providing a more sturdy structure.

Heretofore it has also been proposed to make bending tools with scale means for determining the angle of the bend and the distance of the bend from the end of the tube as measured by the handle, such as are illustrated in Patent No. 2,796,785; Netherlands Patent No. 53,402, of October 16, 1942, and Patent No. 2,887,917. These were, however, difficult to use and could not be used with the exactitude required in certain operations. By the present invention we have provided an improved scale means which enables the bends to be performed more accurately and with a minimum of skill.

Still other advantages of the invention, and the invention itself, will become more apparent from the following description of some embodiments thereof, which description is illustrated by the accompanying drawings and forms a part of this specification.

50 In the drawings:

FIG. 1 is an enlarged elevational view of a bender constructed according to our invention, with a tube to be bent illustrated in dashed lines and also showing in dashed lines an alternate position taken by the shoe at the start of a bending operation;

FIG. 2 is a fragmentary view of the mandrel end of the bender of FIG. 1, showing the shoe rotated to the position taken in making a 90° bend;

FIG. 3 is a sectional view taken on the line 3—3 of FIG. 2;

FIG. 4 is a similar view taken on the line 4—4 of FIG. 1;

FIG. 5 is a section on the line 5—5 of FIG. 1;

FIG. 6 is a view of a holding hook removed from the mandrel;

FIG. 7 is a view similar to FIG. 1, illustrating a modified form of shoe handle;

FIG. 8 is a fragmentary view of the mandrel end of the bender of FIG. 7, showing the position taken by the bending shoe and handle at the start of a bending operation;

FIG. 9 is a plan view of a link used to connect the bend-in shoe to the mandrel;

FIG. 10 is an elevational view of another form of the invention;

FIG. 11 is a fragmentary elevational view of the mandrel end of the bender of FIG. 10, taken at right angles thereto;

FIG. 12 is a section taken on the line 12—12 of FIG. 10; and

FIG. 13 is a fragmentary view of the end of the handle illustrating a scale useful in making bends.

Referring now to the drawings, throughout which like parts are designated by the reference characters and more particularly to FIGS. 1 to 6 inclusive, the bender of our invention is illustrated as including a mandrel 10, which is of generally circular formation having a portion removed on a chord at 11 and in which, as best shown in FIG. 4, a handle 12 is secured by a pin 13. The mandrel 10 is provided with the usual tube receiving groove 14 which extends peripherally around the mandrel. The groove is of conventional shape, the bottom having a transverse radius the same size as the transverse radius of the tube and the sides of which extend slightly beyond the center of the tube as is well known in the art. The mandrel is also provided with markings which start at 0°, this being on a line extending on a radius through the center of the mandrel and which line is normal to the handle, and ending on 180°, whereby the degrees of bend of a tube may be determined in the conventional manner.

Adjacent the mandrel, the handle is formed with a portion of reduced cross-section at 15 to provide a cylindrical bearing surface for a tube engaging hook 16. The tube engaging hook or latch is provided with an eye 17 which is rotatably journaled on the part 15, a spring washer 18 being interposed between the shoulder formed by the reduced portion 15 and the main body of the handle. The washer exerts friction between the latch and the handle enabling it to be adjusted to and stay in any desired position. The latch is provided with an arm 19 for finger or thumb engagement and a hook 20 which is designed to engage with a tube T when swung over the tube. As best shown in FIG. 6, the tube engaging face 20a of the hook provides a cam surface which tightens its engagement with the periphery of the tube as the hook is rotated counterclockwise into engagement therewith. That is, the surface 20a is on a plane which departs from a vertical plane by a few degrees, as illustrated in FIG. 6.

The preferred manner of making the tube engaging surface of the hook is to make a curved surface that is generated by a radius which has its axis slightly below the center of the eye 17, as shown for the hook in FIG. 12. The design is such that the surface provides a "sticking taper" for engagement with the tube surface which holds without slipping.

The above construction also enables the manufacturing tolerances to be increased because the slant of the cam surface is such that the tube is gripped at some point on its surface and does not have to be completely closed upon the tube to provide a good holding effect. It also lends itself to manufacture by being made of solid material or from a series of stampings to provide a laminated structure, see FIG. 10.

The handle is offset to the left at 22 and then continues in a straight line which is parallel to a line drawn through the axis of the mandrel and at 90° from the starting point "0" for making bends. It is provided with a tube seat 23 which extends lengthwise of the handle substantially co-extensive with the length thereof and which has a cross-sectional formation to conform to the periphery of one side of a tube to be bent. The bottom of this seat is in prolongation of a line extending tangent to the bottom of the groove 14 in the mandrel 10 at the starting point. Preferably this groove has a cross-sectional formation which is an arc of less than 180°, although it could have the same conformation as the groove in the mandrel.

As best shown in FIG. 1, a tube T, which is to be bent, may be placed in the mandrel groove and with one end

portion being seated in the seat 23. At this time the tube is tangent to the bottom of the groove in the mandrel at the starting point. Then, when the hook 16 is rotated counterclockwise the surface 20a comes into engagement with the tube and the tube is pressed firmly into both the mandrel groove and the seat 23. There is more than a mere holding of the tube against moving outward from the handle by the latch, as in the prior art devices; there is a pressure against the tube which holds it against the mandrel at the starting point (0) and the base leg is also pressed into the seat. In this embodiment the holding is further increased by the fact that at the point where the hook engages the tube, the tube is out of contact with both the mandrel and the handle seat 23. Thus the resiliency of the tube assists in locking the tube in place and the holding power is holding the tube against longitudinal as well as swinging movement even though the end that projects into the seat 23 may not necessarily project along the seat very far, because of the frictional engagement of the tube in the bottom of the groove.

It is more common for the tube to extend some considerable distance along the handle in the tube seat 23, and, when it does the operator automatically grasps not only the handle, but along with it, the tube T when he performs a bending operation. It will be noted that during the actual bending operation the pressure on the handle and tube during the bending is increased in a counter-clockwise direction, as viewed in FIG. 1, and therefore the harder the tube is to bend the greater the pressure and the harder the tube is pressed into the groove. Thus the frictional engagement of the tube in the seat is increased and the possibility of longitudinal slipping is greatly reduced. The hook alone, is not entirely relied on at this time for alignment of the tube with the mandrel and its main function is to hold the tube in the mandrel groove and seated in the handle and since the tube is seated in the handle it cannot move longitudinally and is in fixed relation to the mandrel groove and the bend can be made with a greater degree of accuracy.

Another feature of the construction lies in the fact that the handle and the tube to be bent, seated in the handle, may be placed in a vise and clamped during the bending operation. This is frequently desirable when the tubes are of a particularly hard nature.

In addition to the foregoing, the fact that the tube is seated in the handle makes the handle easier to grasp since the tube does not need to be avoided and there is no danger of causing a distortion of the tube as is liable to occur in the prior art devices where the tube is spaced from the handle and where such engagement of the tube and the handle at the same time would be liable to cause bending of the tube in a place where it should not be bent.

It should also be pointed out that the frictional engagement of the tube in the seat 23 may be enhanced by providing transverse grooving of the seat, by knurling the seat, or by etching or sandblasting the seat surface.

The handle also has a scale on it whereby the length of the tube from the center of the tube beyond a bend of 90° to the end of or a mark on the tube in the handle seat may be predetermined. This may include "inch" or "centimeter" markings 24 which are provided on the handle adjacent the seat. The marks extend transversely of the handle and up to the edge of the seat and when the tube is in the seat, the marks actually run directly to the tube, thus enabling the tube to be very accurately positioned in the seat or to be measured by the marking on the handle. For instance, if it is desired to bend a piece of tubing so that the laterally extending portion after the bend is in a plane normal to the axis of the base leg and 6" from the end thereof, the tube is merely placed into the seat with the end of the tube aligned with the 6" mark on the handle and then the tube is bent. The marking on the handle may then be considered as starting from the ex-

treme end of the mandrel at a place parallel to the handle and beyond the center of the mandrel, either at the outer or inner side of the tube after it is bent. In most modern engineering drawings the dimension lines for tubing are usually drawn with the axis of the tube being the place from which dimensions are computed and therefore the scale is preferably placed on the handle with this in mind. In other words, a point on the handle such as the 6" mark, would be 6 inches from the axis of a laterally extending part of a piece of tubing after being bent.

Another feature of the structure resides in the fact that the seat is preferably designed to receive slightly less than 180° of the transverse periphery of the tube. In other words, when a tube is seated in the seat 23 slightly more than one-half of the periphery of the tube as considered in transverse cross section, is disposed outwardly of the seat. When the tube is in this position, the edge of the seat may be used as a straight edge, allowing a longitudinal mark to be scribed on the tube. Then, after a first bend is made and a second bend is to be made with the bends in the same plane, the mark enables the tube to be shifted in the handle and properly lined circumferentially by the previously applied marking to enable the second bend to be made. This enables all the bends to be made in the same plane with each other.

The bending shoe is arranged to be moved around the mandrel in a conventional manner. A link 30, FIG. 9, is provided for connecting the bending shoe to the mandrel. It is provided with an eye 31 in one end, by which it is connected to the mandrel and another eye 32 in the other end by which it is connected to the shoe. It will be noted that the eye 32 is displaced vertically downward from the eye 31, as viewed in FIG. 9. It also has a lateral extension 33 which bears a marking the purpose of which is to enable a mark or marks on the tube to be aligned therewith, whereby certain types of accurate bends may be made, which will later be described. Adjacent the eye 31 there is provided a stop shoulder 34 whereby the link, the shoe and the mandrel may all be placed in certain predetermined positions.

As best shown in FIG. 4, the eye 31 of the link 30 is pivotally secured to the mandrel by a pin which extends through an aperture in the center of the mandrel and the eye. The pin has a cylindrical shank 36 which is rotatably journaled in the mandrel. An enlarged head 37 is disposed outwardly of the shank on one side of the mandrel and between the head and mandrel there is disposed a spring washer 38 which holds the mandrel and link under frictional tension. The shank 36 of the mandrel pin is provided with a reduced diameter portion 39 which extends through the eye 31 and is staked or spun over at 40. The pin, washer, mandrel and link are all assembled and then the pin is either spun or staked at the end preferably to lock the pin to the link. The link is held against the shoulder at the junction of the main body 36 and reduced diameter part 39 by the staking or spinning operation. By this construction, and due to the close fit of the shank 36 in the mandrel, the link is capable of a smooth swingable movement with the pin in the mandrel. The spring holds the pin against endwise movement and thus holds the link pressed against the side of the mandrel with sufficient friction that it may be placed in any desired position and will stay in that position. As can best be seen from FIG. 1, the turning movement of the link 30 is limited by the pin 13 which extends beyond the face of the mandrel and is engaged by the stop shoulder 34 when the link is rotated in a counter-clockwise direction, as viewed in FIG. 1, and where it is shown in the "stop" position.

The forming shoe 43 is rotatably connected to the link and has a handle 44 whereby it may be rotated on the link, and, with the link, rotated around the mandrel, to provide the desired bends. As best shown in FIG. 1, it comprises a shoe body 43 having a longitudinally extending groove 45 of arcuate or semi-circular cross-sec-

tion. To the right of the shoe groove there is provided an eye 46 by which it is pivotally attached to the link 30. The attachment to the link is made in the same manner as the attachment of the link to the mandrel and includes a headed pin 47 which is rotatably journaled in the shoe with a spring washer 48, FIG. 12, between the head and the shoe and with the pin secured in the link as described. There is thus a frictional connection between the shoe and link.

The end of the shoe 43 is cut away obliquely, FIG. 8, so that it intersects the outer edges of the groove 45 at the starting point for a bend when the shoe is in the bend starting position. By this expedient, when the shoe is rotated from the position shown in FIG. 1 into a position for the start of a bending operation, at the time when the shoe comes into engagement with the tube, the movement of the shoe is substantially normal to the axis of the tube. This formation has several advantages in that a greater clearance between the shoe and the mandrel is provided for insertion of a tube between the shoe and mandrel and the mandrel handle does not have to be rotated as far toward the open position of FIG. 1, to enable the tube to be placed in position. Furthermore the process of bringing the shoe into operative engagement with the tube is not accompanied by any distortion or nicking of the tube as the mandrel comes into position or of frictional engagement with the tube at that time which might cause the tube to be moved from the desired position longitudinally relative to the handle and mandrel.

At the start of a bending operation, the link 30 should be in the position shown in FIG. 1, with the stop shoulder 34 against the pin 13. This position is relatively easy to obtain and hold because of the frictional engagement of the link with the mandrel. When the shoe is rotated by the handle to the tube engaging position, a starting mark 51 on the shoe is automatically aligned with the "0" starting mark on the mandrel. The forming groove 45 on the shoe is preferably less than 180° in transverse section and extends for substantially the full length of the shoe as indicated. The shoe is provided with a raised side face or boss 52 which is coextensive with the groove and which extends to and surrounds the pin 47. A pin 53 set into the shoe and extending from the side thereof, FIG. 12, is positioned to engage with the tongue or scale extension part 33 on the link when moved from the position shown in FIG. 1 to that of FIG. 8. This being the time when the bend is to be started. Thus the movement of the shoe toward the mandrel is at all times limited and at no time can the tube be squashed between the shoe and the mandrel and the shoe slides easier over the surface of the tube during the forming operation.

The shoe handle may also be provided with a scale marking 24a and may also be used for measuring the length of the tube T disposed in the seat in the handle since it corresponds to the same marking as at 24. In FIG. 7, the handle 44a is shown as being offset toward the handle 22. This enables the scale 24a on the handle to be brought into close proximity to the tube, when in the position shown in FIG. 7. This also has the advantage, that when the handle is moved to the position shown in FIG. 8 the marking on the shoe handle may be so arranged that they may be used to measure the extension of the tube T beyond the end of the mandrel and also when in the position as shown in FIG. 2 the extension of the tube beyond the bend. Otherwise the disclosure of FIGS. 7 and 8 is identical to that of FIGS. 1 and 2.

As previously mentioned, it is possible with the tool of our invention to provide more accurate formation of a piece of tubing into bends of different degrees and with the desired length of the straight runs of the tube between the bends, and the desired length of tube beyond the bends. This is brought about by the fact that there is a predetermined fixed relation between the link and

the mandrel due to the engagement of the link with the stop pin 13 on the mandrel and the link and the shoe due to the engagement of the pin 53 on the shoe with the extension 33 on the link.

It should also be noted that the marking "0," "45," "R" and "90" on the extension 33 of the link, as shown in the full lines of FIG. 1, are clearly visible for use in conjunction with marks that may be placed on the tube because the markings are outward of the tube and the shoe is in an open position and therefore the tube can be easily moved prior to engagement by the latch 16 or the shoe. The markings being on the link are not apt to become obliterated due to ordinary wear. They are also in a fixed position where they may be correlated with the tube when the shoe is in the open position and at which time the tube may be easily moved and thereby providing a more precise placement of the tube in its proper longitudinal position.

For instance, the mark "0" on the link is on a radius extending through the axis of the mandrel and which radius is normal to the handle and a tube T seated in the seat 23 and the groove in the mandrel. It is also coincident with the tangent point of the tube with the mandrel. If it was desired to make a bend using a given or calculated dimension from a particular fixed point on the tube, which could be but is not necessarily the end, to the start of a bend of any kind, it is merely necessary to measure the distance from the fixed point to the desired start of the bend, mark the tube at this place and then place the tube in the handle seat and mandrel (with the link in the FIG. 1 position) with the mark on the tube opposite to the "0" mark on the link or the mandrel and proceed with the bend.

Toward the end of the extension 33 on the link, is the mark "90." This mark is displaced from the "0" mark by a distance equal to the length of a radius extending normal to the handle and from the center of the mandrel to the axis of a straight tube T, prior to bending, at its tangent point to the mandrel. It is used for making a 90° bend wherein the length from the end or a fixed point on the tube to the center line of the tube after the bend may be determined. In this instance, the length from the fixed point or end of the tube to the axis of the lateral leg of the tube is marked on the tube. The tube is then placed in the mandrel and handle with the mark lined up with "90" mark on the link, the tube is then secured by the hook and the tube bent. This has the advantage that a piece of tubing of any length can be bent to exact dimensions which are usually given on drawings to the center line of the laterally extending portions.

The mark "45" on the link 30 is used in conjunction with making a 45° bend. Such bends are measured from a fixed point on the tube, to the intersection of the center lines of the legs. In making such a bend, a distance is first measured on the base leg of the tube, which will seat in the seat 23, to the point of intersection of the center lines and this point is marked on the tube. The tube is then placed in the bender with the mark at "45" and then the tube is bent. The mark "45" is located on the link at a point beyond "0" on the link which is equal to $\tan L/2 R$ where L is the angle of the bend and R is the radius from the center of the mandrel to the center line of the tube in the bend, at the place where it is tangent to the mandrel at the start of the bend. This formula may also be applied to the position of the "90" mark.

The mark "R" on the link is for making a reverse or "U" shaped bend where the second bend is made from the opposite end of the tube from the first bend. The marking is $.57R$ from the mark "0."

In making a reverse bend, the tube dimension is determined from a drawing including a base leg and a first bend with the end of the tube, or a mark on the tube, a predetermined distance from the center line of the tube after the first bend. This distance is marked on the tube. The tube is then bent using the "90" mark as described.

Then the second dimension on the drawing, which is the distance from the center line of the base leg to the center line of the return bend, is marked on the bent leg of the bent tube.

Now the tube is turned around and the last mark is placed opposite to the "R" mark so that the tube is now being bent from the opposite end and the tube is bent. This provides two parallel legs a predetermined spaced distance apart. It is pointed out that the first bend could have been a 45° bend, in which instance the second mark would have been measured from the intersection of center lines of the tube at the first bend. After the first bend, succeeding bends of any desired number may be made by following the above procedure.

As shown in FIG. 13, the side of the handle 72 opposite to that of FIG. 1, is marked with a series of marks "0" to "4" entitled "gain." These markings are used when it is desired to precut the tube to length prior to bending and thus avoiding waste.

These markings are used in conjunction with the scale 24, and represent the difference in dimensional length of tube needed to make a bend shown on a drawing where the drawing does not show the actual length of tube needed. This is the difference between the length of tube actually needed and the sum of the dimensions shown in the drawing. When a bend is shown in a drawing it may be shown as a right angle. When the tube is bent, however, the bend is actually an arc and there is less tube in the bend than is shown on the drawing and this difference is equal to $.43R$ for each 90° bend. Therefore, the distance between each of the marks "0-1-2-3-4" of FIG. 13 is $.43R$. If a piece of tube is to be bent having two 90° bends, the dimensions from the drawings are first totalled and the tube is marked with a length equal to this total. Then the tube is placed in the handle seat with the marking opposite "2" with the base end of the tube extending in the direction of and beyond the zero mark. The tube is now marked at the "0" mark and cut at this point. The bending of the tube may now proceed in the usual manner and there is no waste.

Another feature of this is the fact that the tube may be precut to the exact length needed to enable it to be bent without any further marking. For example, in making a "U" bend, the cut tube is placed in the bender and the first leg end placed opposite the desired scale mark on the handle and bent. Then the tube is reversed and the second leg of the tube placed opposite the proper scale mark, to give the length of the second leg, and bent.

As previously stated, the invention lends itself to a design wherein the mandrel and handle may be made as an integral unit. FIGS. 10 to 12 inclusive illustrate such a bender. In this instance, the mandrel 70 is provided having a groove 71 of the same cross-sectional conformation as described for the previous embodiments. The body of the mandrel portion is semi-circular in configuration and provided with the usual degrees of bend markings from "0" to "180." The handle 72 is integral with the mandrel and extends from the mandrel at one side of the axis of the mandrel.

Spaced from the mandrel and extending opposite to the base of the mandrel is a boss 73. The boss 73 and the mandrel are both drilled to provide a bore for receiving a latch or hook securing pin 74 on which is swingably mounted a latch 16 having a finger engaging portion 19 and the tube engaging hook 20 with tube engaging face 20a. A spring washer, not shown but which may be similar to that shown in FIG. 1, may be placed around the latch pin 74 between the eye 17 of the latch and the boss 73 or between the eye and the base of the mandrel, to provide friction means for holding the latch in the desired position and also restrain its movement.

The handle 72 is provided with a groove 75 which is of the same conformation as the groove 23 in the device of FIG. 1. The groove is provided with a relief at 75a which extends from a point close to the starting point "0"

and for a short distance toward the end of the handle. This relief is such that in this zone, which is opposite the hook 20 and substantially coextensive in length with the width of the hook, or slightly larger, the tube is unsupported at this point and therefore the resiliency of the tube T assists in the holding engagement thereof by the hook in the mandrel and handle grooves in the same manner as that of FIG. 1.

Adjacent the boss 73 and extending toward the end of the handle there is provided a surface 72a which is preferably flat and is parallel to the bottom of the groove 75. This enables the device, along with a tube seated in the handle, to be gripped in a vise.

The only other material difference between this embodiment and the previously described embodiments, is that the stop pin 76, which corresponds to the stop pin 13 of FIG. 1, is disposed to the left of the axis of the mandrel and the link 77 is provided with a straight edge 78 which engages with the stop pin and limits rotation of the link in a counterclockwise direction.

The handle 44 and its shoe 45 are the same as previously described. The link is attached to the handle and the mandrel in the same manner as described for FIG. 1. The operation of the device is in all respects similar to that of FIGS. 1 and 7.

The latches 16 and 76 may both be of laminated construction as illustrated in FIG. 11. The links 30 and 77 may also be laminated.

Having thus described the invention in some embodiments thereof, we are aware that numerous and extensive departures may be made therefrom without departing from the spirit or scope of the invention as defined in the appended claims.

We claim:

1. A tube bender comprising a mandrel of generally circular configuration having a peripheral tube receiving groove extending from a bend starting point around said mandrel at least 90° and a handle connected to the base thereof, means for holding a tube in said mandrel, a bending shoe for association with said mandrel to bend a tube therein, and a link for connecting said bending shoe to the mandrel, said link being pivotally connected at one end to the mandrel coincident with the axis of said tube receiving groove, stop means on said mandrel for limiting the rotation of said link around said pivot and arranged to stop said link in a predetermined position at said bend starting point for the start of a tube bending operation, said shoe being pivotally connected to the other end of said link, said shoe having a tube engaging seat therein and link engaging means on said shoe for engagement with said link upon a predetermined pivoting of the

shoe on the link and to hold said link and shoe in fixed relation to each other when the shoe and link are rotated around the mandrel, said link being provided with a portion arranged to extend along a tube to be bent when in position in the mandrel and handle and having tube locating markings arranged for juxtaposition to a point on the tube for determining the position of the tube in the mandrel for a bend of a predetermined character.

2. A device as described in claim 1, wherein said link is provided with a projection for engagement with said link engaging means on the shoe which extends parallel to a line extending from the axis of generation of the mandrel groove circumferentially and through the groove at 90° from the starting point and tube locating markings are provided on the link and disposed along the projection arranged for juxtaposition to a selected point on the tube for determining the position of the tube in the mandrel for a bend of a predetermined character.

3. A device as described in claim 2, wherein markings are displaced from the bend starting point by a distance equal to $\tan L/2 R$ where R is the radius from the center of the mandrel to the center of a tube seated in the mandrel and L is the degree of the angle to be bent.

4. A device as described in claim 1, wherein a first marking of said markings is provided extending in alignment with a radius from the axis of the mandrel to the starting point of the bend and a second marking is provided normal to said radius and one radius length from the first marking wherein said radius is from axis of the mandrel to the center line of the tube in the seat at the bend starting point.
